UNITED STATES PATENT OFFICE

2,645,787

CEILING BED

Victor Ray Will, Sacramento, Calif.

Application December 12, 1950, Serial No. 200,469

3 Claims. (Cl. 5—10)

1

This invention is directed to, and it is an object of the invention to provide, a novel disappearing or store-away type bed; the bed being mounted for swinging motion from a position of use on the floor of a room to a stored or out-of-the-way position in a compartment immediately below the ceiling and opening through the adjacent part of one wall of said room.

Another object of the invention is to provide a novel swinging mount for the bed; the mount being arranged so that there is no projection from the wall of the ceiling compartment when the bed is in its stored position.

A further object of the invention is to provide a mount for the bed, as in the preceding paragraph, which permits the bed to be shifted manually, and with only a minimum of effort, between its position of use on the floor, and its out-of-the-way position in the ceiling compartment.

Still another object of the invention is to provide a ceiling bed which is designed for ease and economy of manufacture.

An additional object of the invention is to provide a practical and reliable ceiling bed, and yet one which will be exceedingly effective for the purpose for which it is designed.

These objects are accomplished by means of such structure and relative arrangement of parts as will fully appear by a perusal of the following specification and claims.

In the drawings:

Fig. 1 is an end elevation of the bed and its mount, with said bed as resting on the floor of a room, i. e. in position of use; the wall structure and ceiling compartment being shown in section.

Fig. 2 is a similar view, but shows the bed, in full lines, as partly raised toward the compartment; in broken lines as tilted preparatory to insertion of the bed into the compartment; and in dotted lines as disposed in said compartment.

Fig. 3 is a top plan view of the bed and its mount; the latter being partly in section.

Referring now more particularly to the characters of reference on the drawings, the mount for the bed comprises pairs of spaced, upstanding rigid frames 1, each frame being disposed in a vertical pocket 2 in one wall 3 of a room; said pairs of frames being carried between a header piece 4 and a foot piece 5 in said wall. The space between the frames of each pair thereof is open into one room, indicated generally at 6, while said frames are backed by the wallboard 7 of the other room 8, i. e. the room on the opposite side of the wall 3.

2

The header piece 4 is disposed some distance below the ceiling 9, and a horizontal compartment 10 is formed between such header piece and the ceiling; the compartment being of relatively shallow depth, but of a size in plan slightly greater than that of a single bed or cot, indicated generally at 11.

The compartment 10 includes a bottom 12, and a rear end wall 13; such compartment projecting to some extent into the room 8 immediately adjacent the ceiling, and opening through the wall 3 into the room 6 in symmetrical alignment above the wall pockets 2.

A pair of swing rods 14 project into the corresponding wall pockets 2 between the corresponding pair of upstanding frames 1 therein; such swing rods 14 being pivoted, at their inner ends, to cross pin 15 which span between said frames intermediate the ends thereof and adjacent the back.

When the bed or cot 11 is in use the swing rods 14 extend forwardly and downwardly out of the wall pockets 2 to adjacent the floor 16 in the room 6 outwardly of the wall 3.

At their outer ends the swing rods 14 are connected to a horizontal cross bar 17 intermediate its ends, and rigid supporting arms 18 then upstand from the ends of the cross bar 17, with a slight forward and outward cant (see Fig. 1).

At their upper ends the rigid supporting arms 18 are pivoted at 19 to the upper ends of short end posts 20 affixed centrally to the ends of the rigid mattress frame 21 of the bed or cot 11. Such bed or cot 11 includes corner legs 22 which are normally releasably locked in position, but which when released are swingable about pivots 23 to folded position, as in Fig. 2, extending horizontally inward at corresponding ends of the mattress frame 1, being held in such folded position by clips 24.

When it is desired to move the bed or cot 11 from its position of use, as in Fig. 1, to its stored or out-of-the-way position, as in Fig. 2, the legs 22 are first folded and then the bed or cot is swung upwardly, which upward swinging is counterbalanced by a pair of tension springs 25 connected between each swing rod 14 and points thereabove on corresponding frames 1; such springs being disposed within the wall pockets 2.

When the bed or cot 11 reaches a position adjacent the open end of the horizontal compartment 10, such bed or cot is first tilted upwardly at its inner edge, as shown in broken lines in Fig. 2, and is then inserted in said open end of the compartment 10 and run into the latter, such motion being facilitated by rollers 26 which are

journalized in the outer or front edge of the bottom 12 of said compartment.

When the bed or cot 11 is disposed in the horizontal compartment 10, as shown in dotted lines in Fig. 2, it is in a wholly stored or out-of-the-way position, and the swing rods 15 have no projection forwardly from the wall 3, being received in notches 27 in the forward edge of the bottom 12 adjacent the rollers 26. By reason of this lack of projection, the wall pockets 2, together with the horizontal compartment 10, may have their openings closed by suitable doors, drapes, or the like.

To remove the bed or cot 11 from the compartment 10 and to swing said bed or cot downwardly to a position of use on the floor, the above described procedure is merely reversed.

As will be noted, rods 14 are of dog-leg form, having a bend intermediate their ends arranged to include an upwardly facing obtuse angle. This is an important feature, since it enables the upper portion of the rods, when the bed is in compartment 10, to be vertical and flush with wall 3, and so that they do not cut into header 4 any appreciable amount. At the same time, the lower-end rod mounting pins 15 are set sufficiently back from wall 3 so that they are not very far in front of the suspension points 19 of the stowed-away bed. This, in turn, facilitates the initial bed pulling-out and lowering operation, since the bed only has to move a short distance forwardly to pass beyond dead-center in a lowering direction, without, however, making the horizontal depth of pocket 2 so great as to use up too much valuable space.

With the described ceiling bed and its mount, such bed can be moved between its respective positions manually and with very little effort, and when stored in the compartment 10 the bed is wholly out of the way.

The novel mount for the bed, and the wall pockets 2 and compartment 10, are of such design that they may be readily installed in connection with a wall structure.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. In a disappearing bed assembly including a compartment opening at the front through the wall of a room adjacent the ceiling; a mounting frame, the wall having a pocket opening into the room below the compartment and the frame being secured in the pocket, transversely spaced swing rods pivoted at their inner ends to the frame for swinging between an outwardly and downwardly inclined first position with their outer ends adjacent the floor and an upstanding second position with said outer ends adjacent the open front of the compartment, a bed adapted to be disposed in the compartment, a

horizontal cross bar connected between the outer ends of the swing rods and extending laterally outward from both thereof, rigid supporting arms fixed to the ends of the cross bar, said arms upstanding when the swing rods are in said first position, and means pivotally connecting the supporting arms to corresponding ends of the bed centrally of its sides, the bed being on the floor and in the compartment when the swing rods are in said first and second positions, respectively.

2. In a disappearing bed assembly including a compartment opening at the front through the wall of a room adjacent the ceiling; a mounting frame, the wall having a pocket opening into the room below the compartment and the frame being secured in the pocket, transversely spaced swing rods pivoted at their inner ends to the frame for swinging between an outwardly and downwardly inclined first position with their outer ends adjacent the floor and an upstanding second position with said outer ends adjacent the open front of the compartment, a bed adapted to be disposed in the compartment, a horizontal cross bar connected between the outer ends of the swing rods and extending laterally outward from both thereof, rigid supporting arms fixed to the ends of the cross bar, said arms upstanding when the swing rods are in said first position, short posts upstanding from the ends of the bed centrally of its sides, and means pivotally connecting the supporting arms at their outer ends to the upper ends of said posts, the bed being on the floor and in the compartment when the swing rods are in said first and second positions, respectively.

3. In a disappearing bed assembly including a compartment opening at the front through the wall of a room adjacent the ceiling; a mounting frame, the wall having a pocket opening into the room below the compartment and the frame being secured in the pocket, transversely spaced swing rods pivoted at their inner ends to the frame for swinging between an outwardly and downwardly inclined first position with their outer ends adjacent the floor and an upstanding second position with said outer ends adjacent the open front of the compartment, a bed adapted to be disposed in the compartment, a horizontal cross bar connected between the outer ends of the swing rods and extending laterally outward from both thereof, rigid supporting arms fixed to the ends of the cross bar, said arms upstanding when the swing rods are in said first position, and means pivotally connecting the supporting arms to corresponding ends of the bed centrally of its sides, the bed being on the floor and in the compartment when the swing rods are in said first and second positions, respectively; the bed having corner legs adapted to fold from a depending position to a substantially horizontal position.

VICTOR RAY WILL.
